UNITED STATES PATENT OFFICE.

WALTER C. HADLEY, OF NEW YORK, N. Y.

PHONOGRAPH RECORD.

Application filed July 20, 1921. Serial No. 486,150.

REISSUED

To all whom it may concern:

Be it known that I, WALTER C. HADLEY, a citizen of the United States, and a resident of New York, in the county and State of New York, have invented a new and Improved Phonograph Record, of which the following is a full, clear, and exact description.

The present invention relates to phonograph records and more particularly to phonograph records provided with means co-operating with the tone arm to actuate the brake or stop.

As is well known to those skilled in this art, many phonographs are equipped with "automatic stops," the one most generally employed comprising a rigid post projecting downwardly from the tone arm in position to engage a trip or movable member which 20 in turn operates a brake member. In such devices the movable member is set or adjusted for each record, such adjustment being determined by swinging the tone arm inwardly and positioning the point of the 25 needle approximately at the end of the reproducing surface on the record, and while the tone arm is held in this position, the movable member of the automatic stop is set by being placed in contact with the rigid 30 post projecting from the tone arm. Of course in making this adjustment care must be taken to position the needle accurately 35 with relation to the end of the reproducing surface of the record, but no matter how much care may be exercised, it is almost impossible to accurately position the end of the needle so as to effect the operation of the 40 brake and stop at the desired point, and thus it happens that the stop will be operated at times before the end of the record is reached or for such a period thereafter as to produce a disagreeable scratching of the needle. In such devices also after setting 45 the stop with the exercise of considerable care, the brake member makes a decided jump on the release in starting, thus the "set" point is advanced a varying distance; in most cases, several revolutions, which results many times in stopping before the end 50 of the reproducing surface is reached, or if an effort be made to allow for the jump it may not stop soon enough after completing the record. It is quite difficult moreover to bring the rigid post on the tone arm 55 against the complementary part of the automatic stop in exactly the desired position

and if the adjustment be most carefully made, it is often disarranged by the accidental movement of the tone arm in starting the operation of the machine. As before 60 stated, it is quite difficult to procure accurate, definite setting of the automatic stop and with the utmost care, the operation of the stop will vary many turns of the record because the variation in the construction of 65 the stop in different machines of like make, due to the stiffness of action or wear of parts or otherwise, will cause a variation in the operation of the stop.

It has been proposed to provide phonograph records with a non-reproducing groove constituting a continuation of the groove of the reproducing surface of the record, such non-reproducing groove being at a different and sharper angle designed to 70 impart a relatively quick movement inward of the needle and tone arm and ending in a circular groove where no stop or brake is used, but such additional groove has been 75 found to be ineffective unless the lines are 80 relatively close together and it is found in practice that the needle constantly jumps out of the groove without operating the stop.

The object of the present invention is to provide a phonograph record which may be 85 used on any of the well known phonograph machines provided with an automatic stop, so constructed that it may be possible to accurately set the stop mechanism to be operated at a definite point and having been 90 once set it may be permanently locked and operate with any record embodying my invention no matter what the width of the reproducing surface may be.

Another object of the present invention 95 is to provide a phonograph record with a stop actuating element so constructed and so positioned that regardless of the area covered by the reproducing surface, the universal stop will be operated positively and 100 accurately in all such records shortly after the needle passes from the reproducing surface, and so that a plurality of records may be played without the necessity of resetting the stop mechanism after each record.

A further object is to provide a phonograph record with means whereby the needle after it leaves the reproducing surface will be given a relatively quick lateral movement towards the center of the record, thus moving the tone arm and insuring the operation 110 of the stop mechanism.

To the above ends, the present invention consists of a record for sound reproduction having a section adapted to be engaged by a movable stylus and provided with sound reproducing means, and a stop actuating section adapted to receive the stylus after it passes from the first section, the stop actuating section defining the limits of movement of the stylus within which limits the stylus is operative to actuate an automatic stop device; and it further consists of the devices and combinations of devices which will be hereinafter described and claimed—

The invention is illustrated in the accompanying drawings, in which—

Figure 1 shows a plan view of a disc record embodying the present invention.

Figure 2 is a section on the line 2—2 in Figure 1.

Figure 3 is a section on the line 3—3 in Figure 1.

Figure 4 is a section on the line 4—4 of Figure 1.

Figure 5 is a top plan view of a slightly modified form, a portion of the record being broken away.

Figure 6 is a section on the line 6—6 in Figure 5.

Figure 7 is a section on the line 7—7 in Figure 5.

Figure 8 is a section on the line 8—8 in Figure 5.

Figure 9 is a top plan view of a portion of a disc record illustrating another modification.

Figure 10 is a top plan view of a disc record illustrating another modification.

Figure 11 is a section on the line 11—11 in Figure 10.

Figure 12 is a section on the line 12—12 in Figure 10.

Figure 13 is a top plan view of a portion of a disc record illustrating another modification.

Figure 14 is a section on the line 14—14 in Figure 13.

Similar reference characters will be employed to designate corresponding parts.

In the drawings, I have illustrated my invention as applied to a disc record 1 having the usual grooved surface 2 constituting the sound reproducing surface, and as is well known to those skilled in this art, is in the form of grooves into which the point of the needle or stylus carried by the tone arm of a phonograph is adapted to be engaged, and as such grooved lines are formed spirally, the rotation of the record 1 causes the needle or stylus and the tone arm to gradually move from the outer periphery of the section 2 to the inner periphery thereof. This operation is well understood by those skilled in this art and need not be further set forth.

In all of the records illustrated no matter what may be the width of the reproducing

section 2, it is intended that there shall be a stop actuating groove 3 positioned at the same point with relation to the central spindle opening 4. This groove is similar in every record and as shown, it is provided with a beveled surface 5 which leads in from the upper surface 6 of the record to a shoulder 7, which has a predetermined position, the same in all records. The shoulder 7 preferably defines the area of the central section 8 of the records. Usually the central section 8 is provided with a label 9 on which appears a suitable legend giving the name of the manufacturer and other information. The stop actuating groove 3 is a circular endless groove, but at some point in its circumference, it is provided with an entrance 10 whereby the stylus may pass into the said groove. As soon as the stylus or needle thus passes into the actuating groove 3 and assuming that the automatic stop operated by the tone arm has been properly set, the inclined surface 5 will impart a quick motion to the stylus and the tone arm, the stylus moving towards the centre of the record and will actuate the automatic stop. The actuating groove 3 which may be defined as a stop or brake actuating section, may be of any width and is of substantial width, so that it may form a guide readily discernible and found for setting the automatic stop, for if the point of the needle on the stylus is positioned at any point within the width of the actuating groove, and the brake or stop adjusted for operation with the needle, within that width, then obviously no matter what the length of the record may be or what size or how wide the reproducing surface or section, if the needle or stylus be moved into the actuating groove or section, it will at once bring into operation the automatic stop. Obviously, the actuating groove may have its entrance 10 positioned in close proximity to the end of the reproducing surface or section 2 and the needle or stylus directed therein from the sound producing groove, but the actuating groove 3 may be made relatively narrow as shown and a leading-in groove 11 provided to engage the needle or stylus as it leaves the sound producing groove and quickly lead it through the opening 10 into the actuating groove 3.

In Figure 1 this leading-in groove 11 is shown as a relatively quick acting hook or horn which connects with the sound producing grooves at 12 and quickly leads the needle into groove 3 through the opening 10. In Figure 5 the sound producing section 2 is relatively narrower than that shown in Figure 1 and consequently the leading-in groove 11 will be a somewhat longer spiral hook or horn which at its outer end may be connected by a line or groove 13 with the sound producing groove surface 2.

In Figure 9 means for leading the needle

or stylus into the actuating groove 3 may be, as shown, a spiral groove 14 leading at 15 from the sound producing section 2 in a relatively quick spiral to the entrance 10 of 5 the actuating groove 3.

In Figure 10 the sound producing surface is relatively wide and a spiral groove 16 leading at 17 from the sound producing surface leads the needle into a relatively 10 short leading-in groove 11. In Figure 13 a groove 18 connects at 19 with the sound producing surface and leads the needle into such a position that it will be engaged by the spiral leading-in groove 11. In other 15 words, while the groove 18 does not connect with the leading-in groove 11, yet it will place the point of the needle in such position that the leading-in groove 11 will engage it and throw it quickly into the actuating 20 groove 3.

In operation all that the operator need do is to place the point of the needle at any position in the groove 3, hold it there and set the automatic brake for operation at 25 that point. Having set the brake, if a locking device is provided it may be locked or if a number of records having the present invention are to be played, the same adjustment will affect the operation of the brake 30 in all records of this type and it will be unnecessary to reset the brake for a new record. This is an important advantage for obviously the actuating groove may be of varying widths and in all cases of relatively 35 large area. Having positioned the needle and adjusted the stop or brake, when the needle passes off the reproducing surface, it will in a very short travel of the record be led into the actuating surface and the 40 machine will be instantly stopped or within a very short interval after the sound ceases or after the needle passes off of the reproducing surface.

While in every form of the device I have 45 shown the actuating groove as relatively narrow and furthermore as provided with a leading-in groove, obviously assuming a relatively wide reproducing surface and a relatively wide actuating groove, the entrance

leading from the reproducing surface to the 50 actuating groove may lead directly therein.

The inner margin of the stop actuating groove presents a shoulder 7 which has a fixed and pre-determined position on all the records manufactured under the present invention. This shoulder permits the setting 55 of the stop or brake with great ease even if the phonograph should be used in a dim light or in the dark, for it is easy to locate the proper position for the stylus to actuate 60 the brake or stop by bringing the stylus into contact with the shoulder 7, then moving it a slight distance away from the same, and then setting the stop or brake.

I claim—

1. In a record for sound reproduction, a section thereof adapted to receive a movable stylus and having predetermined limits, within which limits the stylus is operative 70 to actuate an automatic stop device, said section having the bottom thereof inclined with respect to the plane of the record whereby it serves to give the stylus a rapid radial movement.

2. A record for sound reproduction, having a section adapted to be engaged by a movable stylus and provided with sound reproducing groove, and a section adapted to receive the stylus from said first section and having means for operating the stylus 75 to actuate an automatic stop device, the said second section having a pre-determined position with respect to said record, said means of said second section including an inclined surface and a marginal shoulder. 80

3. In a record for sound reproduction, a section thereof adapted to receive a movable stylus and having pre-determined limits, within which limits the stylus is operative 90 to actuate an automatic stop device, said section having the bottom thereof inclined with respect to the plane of the record whereby it serves to give the stylus a rapid radial movement, and a circular stop or shoulder adjoining the inner edge of the stop 95 actuating section.

WALTER C. HADLEY.
